H. S. WILLIAMS

FASTENER FOR AUTOMOBILE HOODS

Filed Feb. 14. 1921

Inventor
Harry S. Williams

By Whittenton Hubbell Whittenton
& Belknap Attorneys

UNITED STATES PATENT OFFICE.

HARRY S. WILLIAMS, OF DETROIT, MICHIGAN.

FASTENER FOR AUTOMOBILE HOODS.

Application filed February 14, 1921. Serial No. 444,822.

To all whom it may concern:

Be it known that I, HARRY S. WILLIAMS, a citizen of the United States of America, residing at Detroit, in the county of Wayne and State of Michigan, have invented certain new and useful Improvements in Fasteners for Automobile Hoods, of which the following is a specification, reference being had therein to the accompanying drawings.

10 It is desirable in automobile construction, that the hood or that portion thereof which is movable for inspection of the mechanism housed thereby, be secured in position by means which hold it in such a manner as to prevent any vibration of the hood, thereby eliminating any tendency to rattling or the like.

20 This invention relates to an automobile hood fastener and to a construction thereof whereby the hood may be quickly and readily opened and as easily secured in closed position by means that effectively prevent any vibration of the movable portion of the hood and any play or rattling of the hood against 25 the parts with which it contacts.

The invention consists in the manners hereinafter set forth, and more particularly pointed out in the claims.

30 In the drawings:

Figure 1 is a view, partially in longitudinal section and partially in elevation, of a portion of an automobile hood with a fastener secured thereto that embodies features of invention:

35 Figure 2 is a view in detail of the latch member and the guide in which it moves; and

Figure 3 is a view in detail of an anchorage.

40 Referring to the drawings, a fitting 1 is secured by suitable means, as rivets 2 or the like, against the side 3 of an automobile hood or a movable portion thereof. A latch 4 is reciprocable longitudinally through suitable guide openings in the fitting 1 in a direction oblique to the plane of the member 3 so as to pass through an opening 5 thereof, the fitting having an outer boss 6 which partially houses the latch, the end 45 walls of the boss forming the guides for the latch and the inner wall 7 acting as an abutment for a spring 8 encircling the latch in compression between this end wall and a suitable shoulder 9 formed on the latch itself. A stop 10 limits the outward move-

ment of the latch which has a convenient hand pull 11 of suitable design at the outer end.

An anchorage 12 is secured to any fixed portion 13 of the automobile within the hood and may be of any design which provides a pair of spring jaws 14 adapted to yieldingly engage over the inner, tapered end portion 15 of the latch 4 when the latter is forced toward them, one of the jaws snapping into a notch 16 when the hand grip 11 is in normal position, and the jaws separating when the hand grip is turned at right angles to the normal position or thereabouts, to permit free withdrawal of the latch. As herein shown, in preferred form the anchorage 12 is a piece of sheet metal folded between its ends to provide slightly convergent arms 17, the inturned upper portions of which constitute the jaws 14.

75 In operation, the parts are so mounted in relation to each other that the spring-projected latch, when forced into interlocking relation with the clip 12, maintains yielding pressure downward and inward, or obliquely inward to the plane of the movable part of the hood and thereby holds the hood to seat in such a manner as to prevent any play between the hood and the parts with which it contacts. Rotation of the latch on its axis permits the ready detachment thereof from the anchorage.

80 As a result a very simple and effective means is provided which holds the hood firmly in position, prevents any rattling of the hood against its abutments, and is simple in construction, and inobtrusive in design.

What I claim as my invention is:

1. The combination of a movable member 95 of an automobile hood, with an anchorage adapted to be secured within the hood and provided with a pair of cooperating yieldable jaws, a fitting adapted to be secured over an opening through the movable member, a latch member longitudinally reciprocable in the fitting through the opening obliquely to the hood for detachably interlocking with the jaws of the anchorage and a spring member in compression between the latch member and the fitting for yieldingly forcing the fitting and member in the general direction of the latch toward the anchorage.

100 2. The combination of a movable member 110

of an automobile hood with a spring clip secured to a fixed portion of the automobile within the hood, a fitting secured to the movable member over an opening therethrough and provided with guide openings, a latch reciprocable longitudinally in the guide openings through the hood opening, and adapted to engage the clip when forced inwardly, and a spring adapted to yieldingly force the hood in the general direction of a length of the latch inwardly when the latter is interlocked with the clip.

3. The combination of a movable member of an automobile hood with an anchorage secured to a fixed part of the automobile within the hood, a fitting secured to the movable part over an opening through the hood, a latch bar rotatable and longitudinally reciprocable in guide apertures in the fitting obliquely to this plane of the hood, provided with a notched and tapered inner end portion adapted to interlock with the anchorage when in normal position, and to disengage this anchorage when turned from normal position, and a spring housed by the fitting and adapted to cooperate with the latch to force the hood inwardly along

the latch when the latter is engaged positively in the anchorage.

4. The combination with a movable member of an automobile hood, of a fitting removably secured to the movable member of said hood, an inclined spring influenced rotatable latch reciprocable through the fitting and the movable member of said hood, yieldable means within the hood to grip said latch, and means carried by the latch adapted to limit the outward movement thereof when the same is disengaged from said yieldable means.

5. The combination with a movable member of an automobile hood, of a fitting removably secured to the movable member of said hood, an inclined spring influenced latch reciprocable through the fitting and movable member of said hood, a pair of spring jaws within the hood adapted to grip the latch in one position thereof, and means for rotating the latch to disengage the same from the spring jaws.

In testimony whereof I affix my signature.

HARRY S. WILLIAMS.
